FLEXIBLE TILE

Kenneth R. Runde, St. Louis, Mo.

Application January 9, 1933, Serial No. 650,805

1 Claim. (Cl. 20—5)

Vitrified tile has long been used for wall surfaces of bath-rooms or the like, but its cost of installation is extremely high as compared with other forms of wall covering. Not only is the cost of the material itself high, but it requires the services of highly skilled workmen to lay the same, and the work proceeds slowly. Further, the settling of the walls of the room in which the tile is installed, or other sources of stress or strain 10 easily causes tile to crack or to have hair-lines appear thereon, and which damage detracts from the otherwise neat and ornamental appearance of the walls.

The instant invention has among its objects to produce a wall covering of a material that will not crack, peel, or have hair-lines appear thereon, or have various other objectionable defects, but upon the contrary will retain its neat and attractive appearance for unusually long periods 20 of time, and be otherwise satisfactory and efficient for use wherever found applicable.

Other objects of my invention are the production of such a tile, that will be easily applied by unskilled workmen, will be quickly laid, and will 25 be economical.

Another important object of my invention is to provide a tile made of asphalt-impregnated paper stock so treated on one surface to prevent the leakage of the oil or asphalt therewith, thereby sealing the same, and a waterproof and decorative coating superimposed on said oil-sealed face, and in which construction there will be no likelihood of oil leaking through to spoil said exposed decorated surface.

A further object of my invention is to provide a flexible tile of the kind described, which will be of polygonal shape, and wherein the peripheral edges will be reduced in thickness or beveled for substantially the entire thickness of the tile, so that when the tile are laid in peripheral abutment to form the wall covering, the grooves thus formed may be filled with a sealing compound to simulate the mortar joints of real vitrified tile, and to anchor the tiles against slippage past one another. In addition, these relatively sharp bevels permit a slight crushing together of adjacent adjoined elements in the event that they should expand, and which will thus take up the expansion without causing the elements to buckle and pull away from the backing wall.

Many other objects and advantages of the invention herein shown and described will be obvious to those skilled in the art to which this in-

vention appertains, from the disclosures herein given.

To this end, my invention consists in the novel construction, combination and arrangement of parts herein shown and described, and more particularly pointed out in the claim. 5

In the drawing, wherein like reference characters indicate like or corresponding parts throughout the views,

Figure 1 is fragmentary elevation of a wall to 10 which my improved tile has been applied;

Figure 2 is a front view of one of the flexible tile elements; and

Figure 3 is a cross-section through adjacent elements, taken substantially along the line 15 3—3 of Fig. 1.

Referring more particularly to the drawing, wherein I have illustrated one of the preferred embodiments of my invention, A indicates one of the walls of a bath-room or the like, that is 20 to be covered with my improved flexible tile elements B.

When laying the usual vitrified tile, it is necessary that a layer of cement or mortar be spread upon the backing wall, as well as between the 25 opposed peripheral surfaces of the tile elements, in order to anchor them in place, and that a level be constantly used to insure laying of the elements in alignment. The tiles do not actually rest upon one another, but upon the layer of 30 cement therebetween, and as the baking heat in making the tiles causes warping, their sides are not true, and this layer of cement between tiles is absolutely essential. Obviously, the laying of 35 these tiles is slow, and hence expensive. Further, the laying around pipes and fittings further complicate the installation and add to the cost materially.

In my improved tile elements, they are not 40 stiff and rigid, but upon the contrary are flexible. They are preferably made of relatively cheap, though durable, material such as paper felt stock rolled or otherwise formed to the desired thickness, and generally impregnated with some oily 45 material such as asphalt or the like to bind the stock together and impart durability to the same. One or both surfaces of the sheets thus formed is coated with any suitable compound or material, as at 1, which will effectively seal the oil 50 or asphalt against leakage therewith, as this impregnation substance has a great tendency to "bleed" or otherwise seep through the sheet to the surface.

Superimposed on the sealed face of the sheet 55

is a second coating 2, as of a pyroxylin paint or the like, which will waterproof the face against moisture penetrating therethrough and as a decorative feature, the said coating being of any desired tint or design to suit various fancies. Thus, the waterproof coating will not be spoiled by oil leakage beneath the same, on account of the sealing coat, of mineral paint or the like, and will retain its effectiveness and appearance as long as the sheet lasts.

The bounding edges of the sheet are preferably beveled for substantially the entire thickness of the sheet, so as to provide a relatively sharp edge about the base of the sheet, as at 3. The bevel 15 may be cut after the elements have been cut to size, or simultaneously therewith, the important consideration being that the resultant elements shall have truly straightline edges and that the width of bevels be uniformly constant.

20 The tile elements are laid to form a wall by applying some sort of a slowly hardening adhesive compound between the elements and the backing wall of the room, and the adjoining elements are laid with their edges in direct abutment without any sort of compound therebetween. In this manner, the laying of the same can be done by unskilled workmen, rapidly and efficiently, as the edge of one tile element forms a gauge for the laying of the adjacent element. In 25 other words, as the elements are placed in direct abutment, the use of a level will not be required, and the elements will be self-spacing and aligning. The edges of all of the elements are cut true and straight and there will be no danger of the elements getting out of line during the installation.

30 When laid in the above manner, the whole wall is covered with the elements, and no openings or spaces are left. The elements may be 35 easily and rapidly cut to permit of fitting around pipes or other fixed structures.

The channels or grooves formed by the adjoined beveled edges extend to substantially the

base of the elements, and into the same may be introduced a suitable filler 4 to seal these beveled edges against leakage of oil or asphalt therethrough and to anchor the blocks against slippage relatively of one another on the wall, said edge filler being applied with any suitable sort of pointing tool or the like as to make a good seal with the beveled edges.

5 The wall thus formed will be extremely attractive and will serve the purpose admirably well, 10 and at much less cost than the true vitrified tiles. The joints are filled with the pointing material, and thus will present a truly hand-made appearance, and as a matter of fact the filler will be even more constant width than with vitrified 15 tile, as there will be no unevenness or warping between adjoined elements to compensate for.

Having thus described my invention, it is obvious that various immaterial modifications may be made in the same without departing from the 20 scope of my invention; hence I do not wish to be understood as limiting myself to the exact form, arrangement, structure, and combination of parts herein shown and described, except as limited by the state of the art to which invention appertains, and the claim hereunto appended.

25 What I claim as new and desire to secure by Letters Patent is:

A flexible tile for interior walls made up of a 30 plurality of such tiles, and consisting of a relatively thin pliant sheet of readily yieldable material, the peripheral edge being relatively sharply beveled for the full thickness of the tile about its entire bounding periphery, so that the individual tiles may be laid into peripheral abutment and whereby lateral expansion of adjacent tiles laid on said wall in such peripheral abutment contact will permit said contacting edges to readily crush without undue buckling of the 35 40 tiles.

KENNETH R. RUNDE.
